UNITED STATES PATENT OFFICE.

FREDERICK M. LASERSON, OF BROOKLYN, NEW YORK, ASSIGNOR, BY DIRECT AND MESNE ASSIGNMENTS, OF ONE-HALF TO LAWRENCE M. STEIN, OF CHICAGO, ILLINOIS, AND ONE-HALF TO WADE STEVENSON, OF BUFFALO, NEW YORK.

PORTABLE GARMENT-MARKING MACHINE.

Application filed December 10, 1921. Serial No. 521,275.

This invention relates to portable garment marking machines. The object of the invention is to provide a generally improved garment marking machine adapted to be carried to the work and to be moved easily and quickly around the work for the purpose of marking the same.

Many machines for marking the positions of lapels, button holes, pockets, and the like, on garments are stationary and the work has to be carried to the machine and manipulated so as to bring the points to be marked in proper position with respect to the machine. The general principle upon which these machines operate is that of sewing a single or double thread through the layers of cloth—the work—after which the thread is cut off on both sides of each layer or thickness of cloth. In this manner a very short piece of thread remains in the cloth to mark the particular place or point desired.

One object of the invention is to provide a machine which may be carried by the operator and thus be moved to the work as well as being operated in and around the work. Another object of the invention is to provide a marking machine of generally improved efficient construction and design. Still another object is to provide a novel and improved mechanism for insuring accurate stitching or manipulating of the thread used in marking.

With the above and other objects in view to be pointed out hereinafter, my invention is embodied in a portable marking machine constructed and arranged as hereinafter set forth and as illustrated in the accompanying drawings in which—

Fig. 1 is a side view, partly in section, of a portable garment marking machine embodying my invention.

Fig. 1^a is a detail view of parts shown in Figure 1.

Fig. 2 is a front end view of the machine with parts broken away.

Fig. 3 is a detail view of parts of the machine shown in Figures 1 and 2.

Fig. 4 is a top plan view of the base of the machine with the upper structure removed.

Fig. 5 is a detail view of a portion of the base showing the parts illustrated in Figure 4 in a different position.

Fig. 6 is a partial sectional view of the base and shows in side elevation some of the parts illustrated in Figures 4 and 5.

Fig. 7 is an isometric perspective view of the stitching head of the machine.

Fig. 8 is a similar view of a modified mechanism for completing the stitching.

Fig. 9 is a side view of the parts shown in Figure 8.

Referring to the drawings and particularly to Figures 1 and 2, the reference numeral 10 denotes a flat oblong base adapted to be moved in under the work. Secured to the base is an upright curved bracket 11 which overhangs and is parallel with the base 10. The bracket 11 carries at its forward end 12 an upright fixed tube 12 having a vertical slot 13. Outside the tube 12 is mounted a movable spring casing 14 which is adapted to slide on the tube 12. The casing 14 carries a collar 15 to which is pivoted at 16 a handle 17, which latter is pivoted at 18 to the bracket 11, the pivot 18 being adapted to slide in a slot 19 in an upright piece 20 attached to the bracket 11.

Within the tube 12 is slidably mounted 80 a needle guide tube 21 which extends through the bracket 11 and projects below the same, where said tube carries a presser foot 22.

The numeral 23 denotes a needle having 85 an eye 24 at its lower end, see Figure 7. The needle is fixed in a guide 25 having a stem 26 secured to a nut 27 which is screwed into and closes the upper end of the casing 14. Between the bracket 11 and the needle guide tube 21 there is interposed a spring 28 the upper end of which acts against a washer 29 which has a tongue 30 projecting into the aforesaid slot 13. A stronger spring 31 is interposed between the tube 21 and the 95 casing 14.

The aforesaid collar 15 carries a screw 95 which projects into the slot 13 under the washer tongue 30. Consequently the upper end of the slot 13 serves as a stop against which the tongue washer 30 is moved by the spring 28, which thus lifts the needle guide tube 21, while the collar 15 is lifted by the spring 31 until the screw 95 abuts the tongue 30, said collar being carried by the tube 14. 105

When the handle 17 is moved down, it carries the needle 23 and the casing 14 downward and by means of the stronger

spring 31 the needle guide tube 21 is also moved downwardly compressing the weaker spring 28. Consequently the needle and the tube 21 are moved downwardly below the bracket 11 is shown in dotted lines in Figure 1. The downward movement of the presser foot ceases when it strikes the work, that is the layers of cloth which is indicated at 32 in Figure 1. Further downward movement of the handle 17 causes further compression of the spring 28 and moves the needle downward through the work against the tension of the spring 31.

On the pivot 18 is suitably mounted a spool 33 from which the thread 34 passes downwardly through a thread guide 35 and to the needle, so that a double thread may be served through the layers of cloth as the needle passes through them.

On the bracket 11 is mounted a sliding lever 36 which is guided by a pin 37 and slot 38. The lever is adapted to be moved back quickly by a spring 39 secured to the lever and to the bracket, but said lever is kept in normal forward position as shown in Figure 1 by the following means.

At the front the lever 36 is bent to one side to form a head 40, see also Figure 3, which carries a pin 41. On the bracket 11 there is pivoted at 42 a latch 43 which is urged upwardly into the position shown in Figure 1 by a spring 44 secured to the underside of the bracket. The latch 43 has a stop 45 which abuts the underside of the bracket 11 and thus limits the upward movement of the latch. As seen in Figures 7 and 3, the forward end of the latch 43 lies in the path of the pin 41 in the lever 36 and thereby normally prevents said lever from sliding rearwards.

When the handle 17 is moved down, it carries with it the collar 15. In the latter is fixed a pin 46. When the handle is at the end of its downward movement, the said pin 46 strikes the latch 43 and moves it downward out of the way of the pin 41 in the lever 36, permitting the said lever to move backward slightly under the influence of the spring 39 until the lever pin 41 strikes the pin 46 as seen in Figure 1^a.

Referring now to Figures 4 to 7 inclusive, the base 10 is provided with an aperture 48 in axial alignment with the needle 23. The base is hollow as shown in Figure 6. Within the base is slidably mounted a stitching head 49, see Figure 7, which is carried by the forward end of a rod 50. The rear end of the latter is bent upward as at 51, Figure 1, and lies against the tail 52 of the aforesaid sliding lever 36. It is obvious, therefore, that so long as the tail 52 is in the path of said rod 50, the latter and the stitching head 49 cannot move rearwardly. The tail 52 moves in a slot 70 in the base.

The head 49 forms a loop 53 and car-

ries a pin 54, a needle catching wall or lug 55 and a stop 56. The head 49 is urged rearwardly by a spring 56 which tends to pull said head diagonally across the opening 48, from the right to the left in Figures 4, 5 and 6. A head guiding lever 57 is pivoted to the base at 58 and is adapted to abut the head as shown. A stop 59 is also carried by the base, see Figures 4 and 5.

The stitching head is operated within a hollow chamber 60 formed within the base around the opening 48. The depending wall 61 of said chamber is provided with a projecting portion 62. 63 is an idler to guide the spring 56, and 64 is a plate for keeping the aforesaid elements in place on the base. The wall 61 surrounding the opening 48 is raised above the base as shown for greater convenience in working in order to raise the layers of cloth at the point of marking.

Normally the parts of the machine are in the position shown in Figure 1. That is, the needle and the presser foot are raised and maintained in raised uppermost position by the springs 28 and 31. When it is desired to mark the work, the machine is moved to the work and positioned until the needle is in axial alignment with the mark on the uppermost layer of the work. This may be ascertained by depressing the handle to register the needle with the marks on the cloth.

Thereafter the handle 17 is depressed, which brings the presser foot 22 down upon the work to compress or press upon the same. Continued downward pressure of the handle causes the needle (which of course has first been threaded) to penetrate the work and the needle continues to move downward until it reaches its lowermost position as shown in Figure 6. At this moment the pin 46 strikes the latch 43 to release the lever 36 which moves slightly to the rear by the spring 39, see Figure 1^a. Thus the tail 52 of the lever 36 is also moved away from the rod 50 and the stitching head is pulled back by the spring 56 into the position shown in Figure 7, where it will be seen that the needle is caught by the head 49 in the corner within the loop 53 adjacent the wall 55. Thereafter the handle is moved upward, permitting the pin 54 to pass between the needle and the loops of thread formed by the upward movement of the needle which occurs at the same time the handle is moved up. As soon as the needle has been raised sufficiently during the said movement to permit the wall 55 of the stitching head to pass under it, the stitching head will continue its rearward motion and the pin 54 in said head will enter the loop of the thread as explained and as the needle passes upwards through the cloth, the pin 54 will retain the loop of thread below the cloth so that a single or double thread stitch will have been made through the layers for marking as explained above.

130

The operation of the parts is simultaneous and instantaneous. The descent of the needle is rapid and its upward movement is rapid. After the needle has reached its extreme upward position, the operator may take hold of a handle 71 secured to the lever 36 and pull the latter forward, thus restoring the parts to normal position. Or if desired, a kicker 72 may be secured to the pivot 18 which will kick the lever 36 forwardly by acting against a pin 73 in the lever. The provision of the kicker 72 makes the entire operation automatic after the operator has depressed the handle.

Many of these machines are in use and the operation of the stitching head to catch and retain the thread has been proven to be perfect, easy and certain.

The success of the operation is due to the fact that the stitching head is first operated to place the pin 54 adjacent the needle, ready to snap quickly to the rear to catch the thread as soon as the needle has moved upward sufficiently to clear the wall 55, during which upward movement of the needle, the loop is formed. And also because the needle itself forms a stop for the stitching head and no third element is required.

Figures 8 and 9 show a modification in which the stitching head 80 is held in forward position by a pivoted latch 81 which lies against a pin 82 in the head 80. When the needle descends, it moves said latch out of the way of the pin 82 and permits the head to move back a little so that when the needle again moves up, the pin 84 may catch the thread and complete the stitch. When the head is restored by the lever 36, the latch 81 is moved upward into the path of the head by a spring 86.

The operation may be summarized as follows: First the needle is threaded, one end of the thread being loose, thereafter the needle with a double thread is moved down through the layers of cloth, the stitching head is automatically operated to position the pin 54 adjacent the needle, after which the stitching head completes its rearward movement to catch the thread. The head is stopped in this rearward movement by the stop 96 striking against the projection 62 of the wall 61. Thus the thread is caught below the garments. The needle then moves upward, leaving a double thread in the garments. At the end of the upward movement of the needle, the parts are automatically restored to normal position, after which the thread between the garments and the spool 33 may be cut off by a cutter 90 and the machine is ready for the next operation.

I claim:

1. In a garment marking machine, the combination with a vertically reciprocatory needle, of a carrier movable in a horizontal plane across the line of needle reciprocation,

a needle thread loop retainer fixed to said carrier, a spring for moving said carrier in one direction, means including a latch for locking said carrier against movement by said spring, means for actuating said needle including a device for releasing said latch as the needle approaches its lowermost position whereby the carrier will be moved by said spring into contact with the needle to locate the retainer in entering position relative to the needle thread loop and whereby said carrier will be subsequently moved by said spring across the line of needle reciprocation during the first part of the upward stroke of the needle to carry said loop therewith, and means for returning said carrier and latch to their initial positions during the latter part of the upward stroke of the needle.

2. In a garment marking machine, the combination with a vertically reciprocatory needle, of a carrier movable in a horizontal plane across the line of needle reciprocation, a needle thread loop retainer fixed to said carrier, a spring for moving said carrier in one direction, means including a latch for locking said carrier against movement by said spring, means for actuating said needle including a device for releasing said latch as the needle approaches its lowermost position whereby the carrier will be moved by said spring into contact with the needle to locate the retainer in entering position relative to the needle thread loop and whereby said carrier will be subsequently moved by said spring across the line of needle reciprocation during the first part of the upward stroke of the needle to carry said loop therewith, a lever for reciprocating said needle, means actuated by said lever for returning said carrier to its initial position during the latter part of the upward stroke of the needle, and a spring for returning said latch to its initial position during the latter part of the upward stroke of the needle.

3. In a garment marking machine, the combination with a frame having a base and a fixed overhanging arm, of a reciprocatory needle supported by said overhanging arm and movable vertically relative thereto, a presser foot normally disposed below said needle and movable vertically relative to said overhanging arm, and a connection between the needle and the presser foot including a spring whereby the needle will continue to move downwardly subsequently to the presser foot engaging the work.

4. In a garment marking machine, the combination with a frame having a base and a fixed overhanging arm, of a reciprocatory needle supported by said overhanging arm and movable vertically relative thereto, a presser foot normally disposed below said needle and movable vertically relative to said overhanging arm, a connection between

the needle and the presser foot whereby the needle will continue to move downwardly subsequently to the presser foot engaging the work, said connection including vertically disposed telescopic sleeves, the inner sleeve being fixed to the overhanging arm, a barrel extending into the inner sleeve and carrying said presser foot, and separate coiled springs respectively located in said inner and outer sleeves, the spring in the outer sleeve being relatively stronger than the spring in the inner sleeve, said needle being carried by the outer sleeve and extending downwardly through the barrel of the presser foot.

5. In a garment marking machine, the combination with a base having a needle opening at one end and having a slot formed in the other, of a horizontally movable carrier located under the needle opening, a rod having its front end fixed thereto and its rear end having a sliding engagement in said slot, a needle thread loop retainer mounted on said carrier, an actuating arm engageable with the rear end of the rod, a spring between the base and carrier, and a link having one end pivoted on the base and the other end engaging the carrier and cooperating with said spring to move the carrier in a path across said needle opening.

6. In a garment marking machine, the combination with a base having a needle opening at one end and having a slot formed in the other, of a horizontally movable carrier located under the needle opening, a rod having its front end fixed thereto and its rear end having a sliding engagement in said slot, a needle thread loop retainer mounted on said carrier, an actuating arm engageable with the rear end of the rod, a spring between the base and carrier, a link having one end pivoted on the base and the other end engaging the carrier and cooperating with said spring to move the carrier in a path across said needle opening, and stops fixed to said base for respectively limiting the extreme limits of movement of said carrier.

7. In a garment marking machine, a base, needle supporting means, a threaded needle therein, a tube surrounding said needle, a presser foot supported on said tube, means for operating said tube and needle to cause the presser foot to contact with the garments and to cause the needle to penetrate the latter with a double thread, means for withdrawing said needle to cause the said thread to form a loop adjacent the one side of the garment and within the said base, thread engaging means located within the latter, devices for operating said thread engaging means simultaneously with the operation of the said tube and needle to position said thread engaging means in contact with said needle, said devices also serving

as a means for causing said thread engaging means to engage the said formed loop of thread.

8. In a garment marking machine, a base, needle supporting means, a threaded needle therein, a tube surrounding said needle, a presser foot supported on said tube, means for operating said tube and needle to cause the presser foot to contact with the garments and to cause the needle to penetrate the latter with a double thread, means for withdrawing said needle to cause the said thread to form a loop adjacent the one side of the garment and within the said base, thread engaging means located within the latter, devices for operating said thread engaging means simultaneously with the operation of the said tube and needle to position said thread engaging means in contact with said needle, said devices also serving as a means for causing said thread engaging means to engage the said formed loop of thread, and means operative upon the complete withdrawal of the needle from the garments to automatically move said thread engaging means into normal position.

9. In a garment marking machine, a threaded needle, means for operating it to carry a double thread through the garments, thread engaging means, a spring for operating the latter to engage the thread and means for resetting said spring to repeat the said operation of the thread engaging means.

10. In a garment marking machine, needle supporting means comprising a fixed member, a tube secured thereto, a needle guiding tube movably supported within said fixed tube, a spring for maintaining said movable tube in predetermined upper position, a presser foot on the bottom of said tube, an outer needle carrying tube adapted to telescope outside of said fixed tube, a spring interposed between said needle guiding tube and said needle carrying tube, said last named spring being of greater strength than said first named spring, a needle secured to said needle carrying tube and mechanism for operating the said needle guiding and needle carrying tubes to cause the needle to penetrate the garments and to cause the presser foot to compress the garments in advance of the needle.

11. In a garment marking machine, a fixed support, a threaded needle, needle supporting means slidably mounted on said support, needle guiding means slidably mounted on said support and means for simultaneously operating said needle supporting means and said needle guiding means.

12. In a garment marking machine, a fixed support, a threaded needle, needle supporting means slidably mounted on said support, needle guiding means slidably mounted on said support, means for simultaneously operating both of said needle supporting

and guiding means, and means permitting said needle guiding means to yield during the operation thereof upon encountering the material to be marked by the said machine.

5 13. In a garment marking machine, a fixed hollow support, a needle carrying member slidably mounted within the same, a needle guiding member slidably mounted within said support and means for operating the 10 said two slidably mounted members on the said support.

14. In a garment marking machine, a fixed supporting member, needle guiding and needle carrying means mounted on said member, mechanism for operating the said 15 two means in slidable relationship to each other and to the said member, and yielding means interposed between the said needle guiding means and the needle carrying means.

FREDERICK M. LASERSON.
